Patented Oct. 24, 1967

208,975

AUXILIARY SUN VISOR

Emil J. Koubale, Rte. 3, Box 482,
Junction City, Oreg. 97448

Filed Apr. 4, 1967, Ser. No. 6,521

Term of patent 14 years

(Cl. D14—6)

FIG. 1

FIG. 2

FIG. 3

FIG. 4

FIGURE 1 is a top view of an auxiliary sun visor, showing my new design.

FIGURE 2 is a front elevational view thereof.

FIGURE 3 is an edge elevational view of the right end of FIGURE 2, and

FIGURE 4 is a rear elevational view of FIGURE 2 rotated through 180 degrees.

I claim:

The ornamental design for an auxiliary sun visor, substantially as shown.
